Attorneys.

UNITED STATES PATENT OFFICE.

GEORGE L. BALLARD, OF NORRISTOWN, PENNSYLVANIA, ASSIGNOR TO WILDMAN MANUFACTURING COMPANY, OF NORRISTOWN, PENNSYLVANIA, A CORPORATION OF PENNSYLVANIA.

KNITTING MACHINE.

1,402,038

Specification of Letters Patent Patented Jan. 3, 1922.

Application filed May 10, 1920. Serial No. 380,834.

To all whom it may concern:

Be it known that I, GEORGE L. BALLARD, a subject of the King of Great Britain, and a resident of Norristown, in the county of 5 Montgomery and State of Pennsylvania, have invented certain new and useful Improvements in Knitting Machines, of which the following is a specification.

The invention relates to knitting machines and particularly to the type of machine having that style of presser for the needle beards which is pivotally supported at its lower end and stands up in front of the needle.

15 The invention is shown in the accompanying drawings, in which:

Figure 1 is a vertical sectional view of a part of a needle cylinder and sinker ring with my improved form of needle presser combined therewith.

Fig. 2 is a detail view of the presser.

Fig. 3 is a detail sectional view of the sinker ring with the yarn guide mounted thereon.

25 Fig. 4 is a sectional view of the member having the guide eye for the yarn.

Fig. 5 is a plan view in the nature of a diagram showing a part of the needle row, the pressers and yarn guiding device.

30 Fig. 6 is a bottom plan view of the yarn guide shown in Fig. 5.

In these drawings, 1 indicates a needle cylinder of substantially ordinary form and 2 spring beard needles slideable vertically in 35 slots 3 of the cylinder, these needles being operated in any suitable way as by the jacks 4. 5 indicates sinkers and 6 the ring or bed for the sinkers, and these sinkers may be of the form which performs the two-fold 40 function of sinking the yarn and holding the web. My improved presser is shown at 7, this having a shoulder at 8 extending to the front of the main body of the presser and above its partly circular shaped lower 45 end 9. This partly circular lower end forms the pivot of the presser upon which it rocks in its movement towards and from the needle during the pressing action and it will be observed that this partly circular lower end 50 presents a curved surface at 10 which projects beyond the substantially upstanding edge 11 of the presser. This rounded surface 10 bears upon the needle shank while the shoulder 8 takes under a shoulder or rib 12 on

the inner face of the sinker ring. The presser rests upon the ledge 12' formed on the sinker ring which the rib 12 overhangs. The presser is held in place by the formations just described, the needle presenting by its shank a bearing surface for the inner side of the 60 lower end of the presser which keeps the shoulder 8 under the rib 12. This construction avoids the use of the spring band which is ordinarily employed for holding the presser in place. In order to remove any 65 one of the pressers, it is simply necessary to remove the corresponding needle and this will afford sufficient space to permit the lower end of the presser to be moved inwardly towards the axis of the machine so 70 that the shoulder 8 may then be drawn out from under the overhanging rib 12 and thereupon the presser may be raised and thus be withdrawn from the machine.

The presser is not located in the needle 75 slot, because the walls of the slot is cut away at the region of the presser, excepting a small projecting portion at x' at the verge of the cylinder to guide the needles. Pressers in the needle slot gives rise to considerable trouble, because a slight bend or uneven thickness will cause the presser to stick, but this is avoided in my construction.

The yarn is fed to the needles through a 80 yarn guide consisting of a plate 13 having a downwardly extending rib 14 at its inner edge, this rib having a beveled face at 15. The yarn guide eye 16 is formed through this rib of the plate and there may be a plurality of these guide eyes as shown at 16 and 16', Figs. 5 and 6. The rib 14 is of cam-shape as shown at 17, Fig. 6, and dotted lines Fig. 5, this cam formation tapering toward the left in Fig. 5, so that as the pressers 7 come along in the direction of the arrow in said Fig. 5, they will be lined up or moved outwardly in respect to the axis of the machine should any of these pressers have become dislodged slightly from their normal positions. This will cause the upper 90 ends of the pressers to pass the guide eyes for the yarn without interference therewith.

A portion of the sinker wave is indicated at x and a part of the presser cam at y .

I claim as my invention:

1. In a knitting machine having spring beard needles, a cylinder, a ring having a ledge and a rib overhanging the same and

pressers individual to the needles pivotally supported at their lower ends on the ledge and having movement at their upper ends to and from the needle beards, said pressers 5 at their lower portions bearing upon the needle shanks and having shoulders engaging under the rib to be held in place thereby, said pressers being adapted to be removed by first removing the needles, there- 10 by providing space to permit the displacement of the shoulders of the pressers from under the rib of the ring.

2. In combination in a knitting machine, 15 spring beard needles, a cylinder, a series of pressers, one for each needle, said pressers at their lower ends bearing upon the needle shanks, and on their outer edges adjacent their lower ends, having shoulders projecting beyond the said outer edges, a fixed 20 rib overlying the shoulders for holding the pressers in place, and cam means engaging the upper portions of the pressers for operating them, substantially as described.

3. An individual presser for a spring 25 beard needle comprising a member terminating at its lower end in a rounded portion forming a pivot bearing portion at said lower end, and a shoulder on its outer edge adjacent the rounded end to be engaged by 30 holding means, the rounded portion extending beyond the outer and inner edges of the main part of the presser, substantially as described.

4. In combination in a knitting machine, 35 a series of spring beard needles, a carrier therefor, a series of beard pressers pivotally supported at their lower ends and upstanding therefrom, a yarn guide, and cam means for engaging and moving the upper ends of 40 the beard pressers outwardly to normal position to pass the yarn being fed, substantially as described.

5. In combination in a knitting machine, 45 a series of spring beard needles, a series of beard pressers individual to the needles pivotally supported at their lower ends and upstanding therefrom, a yarn guide plate having a guide eye for directing the yarn to the needles and a cam-shaped rib on the 50 lower side of the yarn guide plate for engaging the upper ends of the upstanding pressers to move the same outwardly to normal

position to pass the yarn being fed to the needles, substantially as described.

6. A presser for spring beard needles having a lower edge face curved on the arc of a circle of larger diameter than the width of the main part of the presser, said curved edge extending beyond the plane of both the inner and outer edges of the said main part, 55 and a shoulder at the front of the presser connecting the curved edge with the front edge of the main part, substantially as described.

7. In combination spring beard needles, 65 a presser having a rounded lower enlargement with a shoulder on its outer side, a frame member having a bearing for said rounded enlargement and a rib overhanging the same, said presser being retained in place 70 by the enlargement engaging the needle shank on one side and the shoulder engaging the rib on the other side, the removal of the needle permitting the disengagement of the shoulder from the rib and the removal 75 of the presser, substantially as described.

8. In a knitting machine and in combination, individual rocking pressers upstanding in front of the needles, a frame member having a rib engaging a portion of the presser 80 near its lower part to hold the same in place, spring needles upon which the lower portions of the pressers bear to be thereby held in engagement with the rib, and cam means for engaging the upper portions of the 85 pressers to rock them on their lower portions, the removal of the pressers being dependent on first removing the corresponding needles, substantially as described.

9. In combination in a knitting machine, 90 a cylinder, a ring surrounding the cylinder, spring beard needles, a presser for each needle, each of which has a rocking bearing upon a portion of the ring and also upon the needle shank, said ring having a rib, the said pressers each having a shoulder to take under the rib whereby the presser will be held in place by engaging the needle on one side and by its shoulder at its other side engaging under the rib, the removal of the needle permitting disengagement of the shoulder from the rib for the removal of the presser. 95

In testimony whereof I affix my signature.
GEORGE L. BALLARD,
